DESIGN FOR A BILLFOLD

Robert H. Rolfs and Wentworth H. Weaver, West Bend, Wis., assignors to Amity Leather Products Co., West Bend, Wis.

Application January 20, 1936, Serial No. 60,694

Term of patent 3½ years

To all whom it may concern:

Be it known that we, Robert H. Rolfs and Wentworth H. Weaver, both citizens of the United States, residing in West Bend, in the county of Washington and State of Wisconsin, have invented a new, original, and ornamental Design for a Billfold, of which the following is a specification, reference being had to the accompanying drawing, forming part thereof.

In the drawing:

The single figure is a perspective view of the billfold, showing our new design.

The design appears wholly on the front side of the billfold and the reverse side of the billfold is plain. The billfold has only the thickness disclosed at the lower edge of the figure.

We claim:

The ornamental design for a billfold, as shown and described.

In testimony that we claim the foregoing we have hereunto set our hands at West Bend, in the county of Washington and State of Wisconsin.

WENTWORTH H. WEAVER.
ROBERT H. ROLFS.
